(57) **CLAIM**

The ornamental design for a sensor system, as shown and described.

DESCRIPTION

FIG. 1 is a perspective view of a sensor system with output device according to a first example embodiment of the design;

FIG. 2 is a top view of a sensor system of the embodiment of FIG. 1;

FIG. 3 is a bottom view of a sensor system of the embodiment of FIG. 1;

FIG. 4 is a side view of a sensor system of the embodiment of FIG. 1;

FIG. 5 is a side view of a sensor system of the embodiment of FIG. 1;

FIG. 6 is a front view of a sensor system of the embodiment of FIG. 1; and,

FIG. 7 is a rear view of a sensor system of the embodiment of FIG. 1.

The broken lines with the various embodiments of the claimed design and the spaces therein are included for illustrating environmental aspects only and form no part of the claimed design.

The article is shown with a symbolic break in its length. The appearance of any portion of the article between the break lines forms no part of the claimed design.
